UNITED STATES PATENT OFFICE

LOUIS L. PRATT, OF PHILADELPHIA, PENNSYLVANIA, ASSIGNOR TO C. H. WHEELER
MANUFACTURING COMPANY, OF PHILADELPHIA, PENNSYLVANIA, A CORPORATION
OF PENNSYLVANIA.

CONDENSER.

1,145,334.

Specification of Letters Patent.

Patented July 6, 1915.

Application filed June 8, 1914. Serial No. 842,545.

To all whom it may concern:

Be it known that I, LOUIS L. PRATT, a citizen of the United States, residing in the city of Philadelphia, county of Philadelphia, and State of Pennsylvania, have invented a new and useful Condenser, of which the following is a specification.

My invention relates to condensers, and particularly surface condensers, used for condensing vapor or steam into liquid, as for example, for condensing into water the exhaust steam from a steam engine, turbine or other steam delivering device.

It is the object of my invention to provide a condenser in which the steam flows toward a central air lane through paths of minimum length and to provide a structure whereby the back pressure or drop in pressure within the condenser shall be a minimum; and it is a further object of my invention to provide bridges or partitions in the cooling water end boxes in such arrangement as to prevent air pockets in the circulating system and, preferably, to provide a plurality of cooling water passes disposed side by side as distinguished from passes superposed one above the other. These and other objects and advantages of my invention are obtained by the structure hereinafter described.

For an illustration of some of the forms my invention may take reference is to be had in the accompanying drawings, in which:

Figure 1 is a longitudinal cross sectional view through a condenser embodying my improvements adapted to the wet vacuum system. Fig. 2 is a cross-sectional view, some parts in elevation, taken on the line 2—2 of Fig. 1. Fig. 3 is a cross-sectional view taken on the line 3—3 of Fig. 1. Fig. 4 is a longitudinal cross-sectional view of a condenser similar to that of Fig. 1 but adapted to the wet and dry vacuum system. Fig. 5 is a cross-sectional view, some parts in elevation, taken on the line 5—5 of Fig. 4.

Referring to Figs. 1, 2 and 3, S is the condenser shell, generally of cast iron, which has the end portions s of smaller diameter. E is the inlet for the exhaust or other steam or medium to be condensed. To the end portions s of the condenser shell are secured the cooling water boxes B and B', the tube sheets M, of Muntz's metal or other suitable material, being held between the flanges on

the boxes B, B' and the end portions s. Into these tube sheets M are fitted the tubes t of brass or other good heat conducting metal secured in the sheets or plates M by the usual ferrules or other fastening means, not shown. As here illustrated the tube sheets M are circular so that the tubes t occupy more or less completely a circular area as indicated in Figs. 2 and 3, forming a circular tube bank. The circular bank of tubes, it will be seen, from Fig. 3, is not concentric with the main shell S but is disposed near the bottom of the shell S so that from the exhaust inlet E to the bottom of the shell S there is a free and ample space for steam passage which diminishes in cross-section toward the bottom of the shell S. In the bottom of the shell S is the outlet or connection W, for connection to a wet air pump, that is, a pump which removes from the interior of the shell S both the condensate and the air which may have leaked into the steam engine, turbine and connections and some of which may have been present in the boiler feed water. Since both the air and the water are withdrawn through the connection W, the construction of Fig. 1 is for the so-called wet vacuum system.

Making a tight joint with the lower inner side of the shell S is the dam D surrounding and extending to some distance beyond the outlet W. This dam is open at its top and it is through its top that the condensate passes to and through the outlet W. But it will be understood that no condensate will pass out until the level of the condensate in the shell S rises above the top edge of the dam D. This maintains a small mass of condensate in the bottom of the shell S at all times, and the same is refrigerated, that is, chilled to a few degrees lower temperature than the steam at the time it changes into water. The result is that with fluctuations of vacuum and other conditions within the condenser the refrigerated condensate will not easily re-evaporate or return into the condition of steam which, if occurring, would detract from the efficiency of the condenser.

The cooling water enters the box B through the cooling water inlet C into that compartment c of the box B formed by the vertical walls or bridges b, b and the curved or arched top bridge b₁. It then flows from left toward the right, as viewed in

Fig. 1, through all the tubes t which communicate with the compartment c , it being remembered that the bridges b , b and b_1 extend to and fit snugly with the left face 5 of left tube sheet M of Fig. 1. All of the tubes t communicate with the interior of the box B' at the right end of Fig. 1. The water passing through the group g of tubes communicating with compartment c 10 flows into the box B' , and returns in two parallel paths through the remainder of the tubes t , groups g_1 , g_1 , to the compartments c_1 , c_1 , of the box B , as illustrated in Fig. 2. From these compartments the water rises 15 into the space or dome c_2 having top wall b_2 and flows out of the cooling water outlet C_1 .

As shown in Figs. 1 and 3 a baffle plate P is disposed directly below the steam inlet 20 and above tubes t of group g which communicate with compartment c of box B , the angular extent of the plate P being slightly greater than the angular width of compartment c or group g as indicated in Fig. 3. 25 To accommodate the dam D a number of tubes t are omitted as will be seen from Figs. 2 and 3. And tubes are also omitted from group g as, for example, one vertical row, to provide the vertical air lane L . And a vertical row for each of the vertical bridges b , b is omitted because these bridges must tightly contact with the left tube sheet M , Fig. 1, and when so contacting would more or less completely shut off the tubes back of these 35 bridges, and such tubes would be substantially useless and may therefore be omitted.

The steam enters by the inlet E and passes to right and left, as viewed in Fig. 3, to either side of the baffle plate P and thence 40 inwardly between the tubes t , through which the water is flowing, toward the central air lane L . By this arrangement the steam comes first into communication with tubes of groups g_1 , g_1 through which is flowing the 45 warmer cooling water. After passing these tubes and before reaching the lane L any remaining uncondensed steam comes in contact with tubes of group g carrying the colder water and is completely condensed, 50 substantially nothing but air reaching the air lane L . The condensate forms in the bottom of the shell S , and is refrigerated, as above stated, by coming into contact with tubes containing the colder water. The condensate flows over the top edge of the dam 55 D and out through the passage W to the air pump which also removes the air from the condenser in the well known manner. The passage of the steam is through short paths 60 from the space between the shell S and the circular bank of tubes direct to the lane L , the lane L being open to the inside of the dam D and to the outlet W . And during 65 this condensing process the cooling water flows, as above described, through the cen-

tral group g of tubes and returns through the two groups g_1 , g_1 of tubes to the compartments c_1 , c_1 and thence to the outlet C_1 communicating with the space c_2 formed beneath the wall b_2 . The baffle plate P prevents incoming steam from immediately striking the colder tubes t carrying the cold water in the central group g and prevents any warm condensate dropping directly into the dam D to the outlet W .

In Figs. 4 and 5 the general structure and arrangement is the same as that hereinbefore described and similar reference characters indicate similar parts hereinbefore described. In this case, however, the arrangement is for the wet and dry vacuum system. That is, the connection W_1 is the connection for air only to an air pump which removes only air from within the condenser. In this case a dam D_1 extends 85 around and beyond the connection W_1 and is provided with a roof or cap r which prevents any condensate falling in the form of rain or finely divided particles from entering the dam D_1 and passing through opening W_1 to the air pump, the roof r being spaced above the top edge of the dam so that the air can flow over the top edge of the dam beneath the cap r . The condensate collects 90 in the bottom of the shell S with which communicates the receptacle R into which the condensate flows and collects and from which it is removed by any suitable pump to the hot well or other desired point.

As will be noted from Fig. 2, the uppermost tubes t of the lateral return groups g_1 , g_1 are at a level lower than the level of the uppermost tubes t of the middle group and are also at a lower level than the lowermost part of the discharge outlet C communicating with the dome c_2 . As a consequence of these relations any air carried into the system with the cooling water is prevented from forming a pocket which would cause uncovering the interiors of the uppermost tubes t of the lateral groups by displacing the water therein.

From the arrangement of the circulatory system of the cooling water above described it is apparent that the formation of undesirable air pockets is prevented, since the uppermost tubes of the lateral groups are caused to remain filled with water and the uppermost tubes of the middle group as well.

What I claim is:

1. A condenser comprising a shell, cooling water boxes on the ends of said shell, water conducting tubes within said shell, all of said tubes communicating with one of said boxes, a pair of separated vertical partitions in the other of said boxes dividing the same into three compartments and dividing said tubes into three groups side by side, a cooling water inlet communicating with the

middle compartment and through the same with the middle group of tubes, and a cooling water outlet communicating with the other groups, said first named group being 5 disposed between the other groups.

2. A condenser comprising a shell having a steam inlet, a bank of water conducting tubes disposed in said shell, a box on said shell, vertical bridges in said box dividing the same into compartments, cooling water inlet and outlet communicating with said different compartments, a group of said tubes communicating with the compartment between said bridges, the remainder of said 15 tubes divided into groups on opposite sides of said group, whereby cooling water flows and returns through said group of tubes and said groups of tubes.

3. A condenser comprising a shell having 20 a steam inlet, a bank of tubes disposed in said shell, a box on said shell, vertical partitions in said box dividing the same into compartments, cooling water inlet and outlet communicating with different compartments, means causing steam in said shell to first pass between tubes containing water of higher temperature and thereafter between tubes containing water of lower temperature, said last named tubes only being spaced to form an air lane, and an air pump connection communicating with said air lane.

4. A condenser comprising a shell having a steam inlet, a bank of water conducting 35 tubes within said shell, said tubes divided into groups carrying cooling water of different temperatures, those tubes carrying cooling water of lower temperature disposed between groups of tubes carrying cooling water of higher temperature and being spaced to form a vertical air lane, and a connection to an air pump communicating with said air lane.

5. A condenser comprising a shell having, 40 a steam inlet, a bank of water conducting tubes within said shell, said tubes divided into groups carrying cooling water of different temperatures, those tubes carrying cooling water of lower temperature disposed between groups of tubes carrying cooling water of higher temperature and being spaced to form a vertical air lane, a connection to an air pump communicating with said air lane, and a dam within said shell surrounding said connection.

6. A condenser comprising a shell having a steam inlet, a bank of water conducting tubes within said shell, said tubes divided into groups carrying cooling water of different temperatures, those tubes carrying cooling water of lower temperature disposed between groups of tubes carrying cooling water of higher temperature and being spaced to form a vertical air lane, a connection to an air pump communicating with

said air lane, a dam within said shell surrounding said connection, and a condensate receptacle communicating with said shell outside of said dam.

7. A condenser comprising a shell having 70 a steam inlet, a bank of water conducting tubes within said shell, said bank and shell being eccentric with respect to each other, said tubes divided into groups carrying water of different temperatures, those tubes 75 carrying water of lower temperature being spaced to form a vertical air lane, a pump connection communicating with said air lane, a box on said shell, vertical bridges or partitions in said box dividing the same into 80 compartments, and cooling water inlet and outlet communicating with different compartments.

8. A condenser comprising a shell, cooling water boxes on the ends of said shell, 85 a plurality of vertically extending bridges in one of said boxes dividing the same into a plurality of compartments, cooling water conducting tubes within said shell, a group of tubes communicating with the compartment between said bridges, the remainder of said tubes disposed in groups on either side of said group and communicating with the other compartments, a cooling water connection with said first named group, a partition 90 joining said vertical bridges, and a cooling water chamber disposed above said partition and communicating with said other lateral compartments.

9. A condenser comprising a shell having 100 a steam inlet, a bank of water conducting tubes within said shell, said bank being disposed eccentrically with respect to said shell, said tubes divided into a central group and lateral groups, a cooling water inlet 105 communicating with said central group, a cooling water outlet communicating with said lateral groups, and means disposed above said central group between the same and said steam inlet for preventing steam 110 arriving through said inlet from contacting with the tubes of said central group.

10. A condenser comprising a shell having a steam inlet, a bank of water conducting tubes within said shell, said bank being 115 disposed eccentrically with respect to said shell, said tubes divided into a central group and lateral groups, a cooling water inlet communicating with said central group, a cooling water outlet communicating with 120 said lateral groups, and a baffle plate disposed above said central group between the same and said steam inlet.

11. A condenser comprising a shell having a steam inlet, water conducting tubes 125 within said shell, said tubes being grouped eccentrically with respect to said shell, said tubes divided into a central group and lateral groups, a cooling water inlet communicating with said central group, a cooling 130

- water outlet communicating with said lateral groups, and a vertical lane within said central group toward which the entering steam and air flow through said lateral groups and then through said central group.
- 5 12. A condenser comprising a shell having a steam inlet, water conducting tubes within said shell, said tubes being grouped eccentrically with respect to said shell, said tubes divided into a central group and lateral groups, a cooling water inlet communicating with said central group, a cooling water outlet communicating with said lateral groups, a vertical lane within said central group toward which the entering steam and air flow through said lateral groups and then through said central group, and means disposed above said central group between the same and said steam inlet for preventing steam arriving through said inlet from contacting with the tubes of said central group.
- 10 13. A condenser comprising a shell having a steam inlet, water conducting tubes within said shell, said tubes being grouped eccentrically with respect to said shell, said tubes divided into a central group and lateral groups, a cooling water inlet communicating with said central group, a cooling water outlet communicating with said lateral groups, a vertical lane within said central group toward which the entering steam and air flow through said lateral groups and then through said central group, and a baffle plate over said central group and disposed between the same and said steam inlet.
- 15 14. A condenser comprising a shell having a steam inlet, water conducting tubes within said shell, said tubes being grouped eccentrically with respect to said shell, said tubes divided into a central group and lateral groups, a cooling water inlet communicating with said central group, a cooling water outlet communicating with said lateral groups, a vertical air lane within said central group toward which the entering steam and air flow through said lateral groups and then through said central group, an air pump connection communicating with said air lane, a dam surrounding said connection, and a cover above said dam and spaced therefrom.
- 20 15. A condenser comprising a shell, a bank of cooling water conducting tubes disposed in said shell, a cooling water box on said shell, a vertical partition in said box dividing the same into compartments, groups of tubes disposed side by side and communicating respectively with said compartments, a water inlet communicating with one of said compartments, a water outlet communicating with another of said compartments, the topmost tube or tubes communicating with said other of said compartments being disposed at a level lower than the topmost tube or tubes communicating with said one compartment and at a level lower than the lowermost point of said water outlet, said shell having a steam inlet, and said bank of tubes spaced from said shell by distances diminishing progressively with the distances from said steam inlet.
- 25 16. A condenser comprising groups of horizontal water conducting tubes, said groups being disposed side by side, a cooling water inlet connecting with one of said groups, a cooling water outlet connecting with a second group, the topmost tube or tubes of said second group being disposed at a level lower than the topmost tube or tubes of said group connected to the water inlet and disposed at a level lower than the lowermost point of said water outlet.
- 30 17. A condenser comprising a shell, a bank of cooling water conducting tubes disposed in said shell, a cooling water box on said shell, a vertical partition in said box dividing the same into compartments, groups of tubes disposed side by side and communicating respectively with said compartments, a water inlet communicating with one of said compartments, a water outlet communicating with another of said compartments, the topmost tube or tubes communicating with said other of said compartments being disposed at a level lower than the topmost tube or tubes communicating with said one compartment and at a level lower than the lowermost point of said water outlet, said shell having a steam inlet, and said bank of tubes spaced from said shell by distances diminishing progressively with the distances from said steam inlet.
- 35 18. A condenser comprising groups of horizontal water conducting tubes, said groups being disposed side by side, a cooling water inlet connecting with one of said groups, a cooling water outlet connecting with a second group, the topmost tube or tubes of said second group being disposed at a level lower than the topmost tube or tubes of said one of said groups connected to the water inlet and disposed at a level lower than the lowermost point of said water outlet, a condenser shell, said tubes of said groups disposed in a bank eccentric with respect to said shell.
- 40 19. A condenser comprising groups of horizontal water conducting tubes, said groups being disposed side by side, a cooling water inlet connecting with one of said groups, a cooling water outlet connecting with a second group, an air^o lane formed entirely within said first group, and an air pump connection communicating directly with said air lane without passage through the tubes of said second group.
- 45 20. A condenser comprising a shell, a bank of cooling water conducting tubes disposed within said shell, a cooling water box on said shell, vertically extending bridges in said box dividing the same into middle and lateral compartments, said bank of tubes di-

vided into a plurality of groups disposed side by side and communicating respectively with said middle and lateral compartments, a partition joining said vertical bridges at 5 their upper ends, said lateral compartments being in communication with each other through a space above said partition.

In testimony whereof I have hereunto affixed my signature in the presence of the two subscribing witnesses.
